DOUBLE-ACTING GRAVITY HINGE

Kornelius Kalleberg, Brooklyn, N. Y., assignor
to American Gravity Door Closer, Inc., Massa-
pequa Park, N. Y., a corporation of New York

Application April 10, 1952, Serial No. 281,619

7 Claims. (Cl. 16—154)

1

This invention relates to a perfected manner of hinging or hanging a double acting door, gate or closure of any nature and the object thereof is to provide a device of this nature which when swung in either direction freely, may be set to stop at any point in the 180 degree arc of its swing, and when released or returned to its original position centered on the jamb with a minimum of back swing.

The device of this invention is more advantageous than any other type of like device, since there is a minimum of cutting into the door or gate to be hung; in fact in other types it is almost impossible to use the same door or gate as a conventional door once it has been used with an ordinary double acting hinge or closer. In this instance, since there is a minimum of cutting into the stiles of the door, the device may be removed and the door hung in a normal fashion for an ordinary left or right opening door. It is also advantageous in that there are no springs used in the device so that there are no parts which may wear inordinately; due to the simplicity of the design and operation, it does not need a trained mechanic for installation.

The device of this invention is adaptable for any institutional, residential or commercial installation which requires a freely swinging door, and it has overcome the objection of most swinging closures, to wit, the forceful backswing which may upset any one following the person who has just gone through the opening. It operates entirely by gravity and with a minimum of lift or drop which would make for a minimum of wear of the moving parts of the device. Further, this minimum of lift or drop allows for more accurate fitting at the top and bottom of the door or gate. It is also excellent for the installation of doors or closures on metal or masonry floors since it requires no installation to the floor of the opening, all of the device being attached to the bottom and top of the door or gate and the jamb; it also obviates the necessity of conventional type butts on a door of this nature.

For a complete description of this invention, reference is made to the drawings wherein:

Fig. 1 is a side elevation partly in cross-section showing a door and framework in which the door is mounted;

Fig. 2 is an enlarged detail side elevation largely in cross-section showing the lower swivel device;

Fig. 3 is an enlarged detail plan view of the lower swivel device with the door and its parts removed;

2

Fig. 4 is the same view as that of Fig. 2 showing the track member elevated by having its cam rotated to the dotted line position in Fig. 3;

Fig. 5 is an enlarged detail plan view like Fig. 3 but showing the cam rotated to the elevated position for the track member and including a dotted outline of the door in wide open position;

Fig. 6 is a perspective view looking toward the door jamb when the door is in a wide open position and the device is in the tilted position shown in Fig. 4;

Fig. 7 is an enlarged detail exploded view in perspective showing separate parts of the lower swivel device; and

Fig. 8 is an enlarged detail of the upper part of the device partly in cross-section taken along the line 8—8 of Fig. 1, looking toward the door jamb nearest the hinged edge of the door.

A specific embodiment of this invention is illustrated showing a hinge according to this invention used on a swinging door of the type used for kitchen doors or the like.

Fig. 1 shows a door 11 hinged in its frame 12, the bottom of which is made up of the floor or a sill. The door 11 is hinged by an upper swivel means 13 and by a lower swivel device 14. The swivel axes of the upper swivel means and the lower swivel device are in alignment in order to provide proper swinging of the door without any jamming action. There will be sufficient clearance allowed at the top of the door 11 between the door and the top section of frame 12. This clearance is necessary to allow the elevation of the door which takes place upon opening if the lower swivel device is set for automatic closing, as will be more fully explained below.

The upper swivel means 13 is a simple pin type swivel. Referring to Fig. 8 for an enlarged detail view of this swivel means, there is a pin 18 which has an enlarged head 19. Any equivalent type of enlargement which will support the pin 18 in its position shown, but at the same time will allow the pin to be pushed up or raised vertically, may be used in place of the enlarged head 19, e. g. a cross pin or a hole and cotter pin, etc. There are holes or recesses 20 in the pin 18. The purpose of these recesses is to enable pin 18 to be raised vertically by means of any sharp instrument which may engage one of the recesses or holes 20 through a slot 21 located in the door frame, and thereby raise the pin 18 vertically in order to release the door for dismantling. When the door 11 is in place, pin 18 projects into the top of the door. There is a plate 22 fastened to the top of the door in any convenient manner

such as by use of wood screws as illustrated in Fig. 1. The plate 22 has a hole to accommodate the pin 18, and there is a larger hole 23 drilled in the top of the door for a space to leave clearance for the lower end of the pin 18.

The lower swivel device 14 (Fig. 1) consists of a bracket 28 which rests on the floor or door sill as shown in Fig. 2 and which is fastened to the door jamb in any convenient manner such as by means of wood screws as illustrated in the various figures. There is also a pin 29 which is fastened to the horizontal section of the plate 28 in any convenient manner such as by means of a machine screw which passes through a hole in the horizontal section of bracket 28 as illustrated in Fig. 2 and Fig. 4. There is a plate 30 adjacent to the bottom of the door which is similar to upper plate 22. In the same manner as with the upper plate 22, there is a hole through plate 30 to accommodate the pin 29 with a snug yet free swivel fit, and also there is a larger hole 31 drilled in the door to make clearance for the top of the pin 29. In addition, there is a roller wheel 36 which might be any appropriate type of anti-friction device. It has been found entirely satisfactory to use an ordinary ball bearing type wheel which may be fastened to the door by means of an axle 37 which is integrally attached to the lower plate 30. This roller wheel 36 travels on the top edge of a track member 38 and acts as the sole support for the door 11; of course, the swivel pins 18 and 29 act as guides to maintain all movements of the door, except rotation, vertical. The track member 38 is generally circular in shape and has a depression 40 in which the roller wheel 36 rests when the door is in its closed position. The track member 38 is most clearly shown in Fig. 7 and has a smooth, upper surface circular in shape which lies entirely in one place with the exception of depression 40. It is this smooth, circular surface, as well as depression 40, upon which roller wheel 36 rolls in supporting the door 11 throughout its complete range of positions from wide open on one side of the door frame to wide open on the other side. Of course, this smooth surface upon which the roller wheel 36 rides, need only be finished in a smooth condition over that portion or arc encompassing something over 180 degrees of the circle with the depression 40 at the center of this arc. This is obvious when the location of the wheel 36 on the track with the door wide open is noted. The extent of finished surface necessary would vary somewhat with different types of closure having different thicknesses.

The track member 38 has an integrally formed fin 41 at the back thereof which has a notch 42 at the center of the fin. There is also a web 43 formed inside the circular track which fills about half of the space inside the track. There is a U shaped notch 44 in the web 43 which is adapted to fit around pin 29. There is a cut-out section 45 toward the front of the track member 38 (the other side from fin 41). This cut-out section is appropriately shaped to accommodate a wedge-shaped cam 50. There are three lugs 51 which are attached to the vertical section of bracket 28 near the bottom thereof. The central lug 51 is centrally located and is adapted to fit into notch 42 in fin 41 of track member 38, to prevent any lateral movement of the track member 38. Outer lugs 51 are adapted to have the edges of fin 41 slide underneath these lugs to thereby provide a hinging action for the track member 38 when the wedge-shaped member 50 is rotated as will be more clearly described below.

The wedge-shaped cam 50 has a pair of handles 52 which are properly fastened to, or may be integral with, the main wedge-shaped section of the cam 50. There is a web 53 which is also integral with the cam 50 and which has a hole 54 therein, adapted to fit snugly around pin 29. This web 53 with its hole 54 is so dimensioned as to cause the wedge-shaped cam 50 to rotate around directly under the circular portion of track member 38. The purpose of having two handles 52 will be made clear in the description of the operation of the complete device.

Operation

Referring to all of the drawings generally, but most especially to Figs. 5 and 6, the operation of the device will be described. The upper swivel means 13 (Fig. 1) needs no explanation as it is merely a swivel formed by a plate 22 in the top of the door 11 and having a hole therein to accommodate the pin 18 which hangs down from the top of the framework of the door. The lower swivel device 14 (Fig. 1) consists of the various elements previously described in detail and its operation will be clarified by considering the action of the door 11 when the cam 50 is in its extreme positions, one of which is illustrated in Fig. 5. It will be noted that door 11 is shown in one of its wide open positions by dotted lines in this figure. Since the cam 50 is rotated to its extreme counter-clockwise position (as viewed from above), the track member 38 will be elevated or tilted so that the door 11 will tend to swing back to its closed position. This will take place because roller wheel 36 will be resting on an incline, and it will tend to roll down toward the depression 40, where it will come to rest since this is the lowest portion of the track. Fig. 6 illustrates the action of cam 50 when rotated counter-clockwise as viewed in various plan views. It will be noted that the amount of tilting which is given to track member 38 may be varied from an extreme angle, the magnitude of which depends on the design of the cam surface and of the track member following surface, to a position in which the track is entirely level, when cam 50 is rotated to its extreme clockwise position. Such level position is illustrated in Figs. 2 and 3. It will be noted that with cam 50 in this position and the track level, the door will remain in any position where it is placed. This is because, now that the track is level, there will be no tendency for the roller wheel to roll in either direction. Of course, the door will tend to remain closed when placed in that position due to the depression 40. Fig. 2 illustrates the level, no-tilting position, and Fig. 4 shows a tilted position of the track member 38. It will be noted that when the cam 50 is in either of its extreme positions, one of the handles 52 will be hidden by the door (i. e. will be underneath the bottom edge of the door) when the door is closed. Therefore, two handles are provided so that one will always be easily accessible.

It should now be appreciated that this invention provides a smooth, quiet, gentle and positive acting means for closing a door or similar closure; the closing action being gentle tends to eliminate any over-swing and any oscillation of the door when being closed. This is still true when the tilt of the track is made quite steep because the greater the tilting action of the track the greater is the force necessary to open the door away from the closed position and hence the greater the damping action of the device.

A specific embodiment of this invention has been illustrated, but many variations will be evident to one skilled in the art and I do not wish to be limited by the specific showing. Reference is made to the appended claims for the scope of this invention.

I claim:

1. A double acting gravity type closure hinge for a door having a lower swivel device axially aligned with an upper swivel means, said lower swivel device comprising a swivel joint, curved track means located around said swivel joint and having a depression therein to center the closure in its closed position, anti-friction means cooperating with said track means for supporting the closure and a rotatable cam cooperating with said track means to vary the inclination of the track means.

2. The apparatus of claim 1 wherein said cam is pivoted about said swivel joint.

3. A double acting gravity type closure hinge for a door having a lower swivel device axially aligned with an upper swivel means, said lower swivel device comprising a swivel joint, curved track means located around said swivel joint and having a depression therein to center the closure in its closed position, anti-friction means cooperating with said track means for supporting the closure, said track means having an effective surface engaging said anti-friction means and lying in a single plane except for said depression, and a rotatable cam cooperating with said track means to vary the inclination of said effective surface of the track means.

4. The apparatus of claim 3 wherein said cam is pivoted about said swivel joint.

5. The apparatus of claim 3 wherein said track means is circular in shape and wherein said cam is wedge-shaped and is pivoted about said swivel joint.

6. A double acting gravity type closure hinge for a door having a lower swivel device axially aligned with an upper swivel means, said lower swivel device comprising a swivel joint, circular

shaped track means located around said swivel joint and having a depression in the track means to center the closure in its closed position, anti-friction means cooperating with said track means for supporting the closure, said track means having an effective surface engaging said anti-friction means and lying in a single plane except for said depression, a rotatable wedge-shaped cam cooperating with said track means to vary the inclination of said effective surface of the track means, said track means being hinged about one edge, and said track means also having a complementary recess to accommodate said wedge-shaped cam so that the effective surface of the track means may be horizontal when the cam is in one extreme position.

7. A double acting gravity type closure hinge for a door having a lower swivel device axially aligned with an upper swivel means, said upper swivel means comprising a vertically disposed pin the axis of which constitutes the swivel axis of the upper swivel means, recesses in the surface of said pin for engagement by a sharp instrument to effect longitudinal displacement of the pin, said lower swivel device comprising a swivel joint, curved track means located around said swivel joint and having a depression in the track means to center the closure in its closed position, anti-friction means cooperating with said track means for supporting the closure, and a rotatable cam cooperating with said track means to vary the inclination of the track means in order to adjust the speed of closing from zero to a desired maximum.

KORNELIUS KALLEBERG.
